UNITED STATES PATENT OFFICE.

RALPH REED, OF MIDDLETOWN, OHIO.

LETTER-SHEET.

No. 872,370.

Specification of Letters Patent.

Patented Dec. 3, 1907.

Application filed May 31, 1907. Serial No. 376,480.

To all whom it may concern:

Be it known that I, RALPH REED, a citizen of the United States, residing at Middletown, Butler county, Ohio, have invented certain new and useful Improvements in Letter-Sheets, of which the following is a specification.

This invention, pertaining to improvements in that class of letter-sheets providing for self-sealing, will be readily understood from the following description taken in connection with the accompanying drawing in which:

Figures 1 to 8 inclusive illustrate my improved letter sheet when folded to form a packet of what I will term "business" shape, while Figs. 9 to 15 inclusive illustrate the same sheet when folded to form a packet of what I will term "polite" shape.

By a letter or packet of business shape I mean one whose length is very much greater than its width, as distinguished from what I call the polite shape in which the length and width may differ but little or not at all from each other.

Some letter sheets, otherwise admirable, present at some point of the packet a place where by slight manipulation and without damage to the packet some portion of the interior writing may be inspected, and other letter sheets, otherwise admirable, have the defect of requiring two or more gummed flaps to be closed, and other sheets, otherwise admirable, have the defect of involving considerable waste of material. In my improved letter sheet the interior surfaces of the packet are quite inaccessible, and but one gummed flap requires to be dealt with, and the waste of material is so trifling as to be negligible. Furthermore, my improved sheet well lends itself to being folded so as to form a packet of either business shape or polite shape, selectively. In the drawings I show the flat sheet and then the result of the successive foldings, and at each stage I illustrate the folding line for the succeeding folding. All of the folding lines may, if desired, be creased upon the sheet in the process of manufacture, but this is neither essential or specially desirable.

In the drawing, giving consideration to Figs. 1 to 8 exclusively, Fig. 1 illustrates the flat sheet having at one edge a flap 1 provided with gum 2 and extending from one edge of the sheet to about half-way to the opposite edge. 4, indicates a notch at the

outer end of gummed flap 1 whereby that flap becomes provided with a flap-tail. It is manifest that, in cutting such a sheet from larger stock, the flapless locality 3 will correspond with the flap 1 of any other sheet, the consequence being that the notch 4, which is of inconsiderable area, represents the entire wastage of material. 5 represents the first folding line, while 6 and 7 represent sheet-portions on opposite sides of that line. As the first step, portion 7 is to be folded over and down onto portion 6, the folding taking place on line 5. This puts the structure in the condition shown in Fig. 2.

Proceeding to Fig. 2, 8 indicates the second folding line. The part to the right of that line is to be folded over and down onto the part to the left of the line. This leaves the structure in the condition illustrated in Fig. 3.

Going to Fig. 3, 9 indicates the third folding line. The part 10 is now to be folded over and down onto the part 11, the folding taking place on the line 9. This puts the structure into the form shown in Fig. 4.

Going to Fig. 4, 12 indicates the fourth folding line. The part 13 is to be folded over and down onto the part 14, the folding taking place on line 12. This puts the structure into the condition illustrated in Fig. 5.

Going to Fig. 5, 15 indicates the fifth folding line. The gum 2 is to be moistened and then flap 1 is to be folded over and down onto part 13 and stuck there, the folding taking place on line 15. This puts the structure in the condition shown in Fig. 6.

Going to Fig. 6, 17 indicates the sixth folding line. The packet is now to be turned over and flap-tail 19 is to be folded over and down onto the body of the packet and stuck there, this folding taking place on line 17 and leaving the structure complete as indicated in Fig. 7. The packet is now ready for the address and the stamp, and a stamp may, if desired, be stuck over the flap-tail 19.

Fig. 8 illustrates the addressed and stamped packet. An analysis of the conditions will show that the two long edges of the packet are completely closed, and that the end opposite the flap-tail, while open, gives no access whatever to the interior surface of the sheet as will be appreciated from an inspection of Fig. 4, and that the opposite end of the packet has a portion of its extent sealed by the flap-tail, while the remaining portion is thoroughly guarded by the flap 10, seen in

Fig. 4, this flap itself being, in the finished packet, so held by the general binding effected by the gummed flap that it is impossible to withdraw it outwardly so as to effect any exposure whatever of the interior surface of the sheet. Indeed, so far as security against exposure is concerned, the packet is in no sense inferior to an ordinary sealed envelop. Figs. 9 to 15 inclusive, illustrate the same sheet, but folded differently so as to produce a packet of polite shape. In Fig. 9, which indicates the sheet, part 20 is to be folded over and down onto part 21, the fold being on line 22, thus producing a condition illustrated in Fig. 10.

Going to Fig. 10, part 23 is to be folded over and down onto part 24, the fold being on line 25, thus putting the affair into the form illustrated in Fig. 11.

Going to Fig. 11, part 26 is to be folded over and down onto part 27, the fold being on line 28 and bringing the structure into the form shown in Fig. 12.

Going to Fig. 12 flap 1 is to be moistened and folded over and down onto part 29 and stuck there, the folding being on line 30 and putting the structure into the condition shown in Fig. 13.

Going to Fig. 13, and assuming the packet to be turned over, flap-tail 19 is to be folded over and stuck down on the body of the packet, the fold taking place on line 17, thus completing the packet as indicated in Fig. 14, ready for the address and stamp which puts it in the condition indicated in Fig. 15. An analysis of the result of the folding will show that this packet possesses the same element of positive security that obtained with reference to the packet of business shape.

Figs. 8 and 15 illustrate, respectively, the business and the polite shape of packet as arrived at from the sheet proportioned as indicated in Fig. 1 or Fig. 9. The sheet may, if desired, be so proportioned as to secure, in the packet of polite shape, equal dimensions for its sides and ends.

While it is possible, and even desirable in some cases, to so proportion the sheet that it will lend itself to either the business shape or polite shape of packet, no sacrifices are necessary in this regard for it is manifest that a sheet may be so proportioned as to adapt it to one desired shape of packet without regard to whether or not it will lend itself to any alternative shape of packet.

In the drawing the notch 4 is triangular, resulting in an angular tail-flap capable of being entirely covered by a postage stamp. The notch may, if desired, be a mere slit so that the end flap has a more liberal area and regular shape, in which case the tail-flap would be adapted to have a postage stamp impressed directly upon it.

I claim:—

A letter-sheet having a rectangular body-portion having a gummed flap projecting laterally from one end of one edge to a point about midway of the length of that edge, the outer end extremity of the flap being notched inwardly from the end of the flap and the free long edge of the flap being parallel with the edge of the body-portion from which it projects, the sheet being adapted to be folded and sealed as set forth.

RALPH REED.
